UNITED STATES PATENT OFFICE.

CHARLES J. EISENHAUER, OF LEBANON, PENNSYLVANIA.

KNIFE-SHARPENER.

1,365,161.

Specification of Letters Patent.

Patented Jan. 11, 1921.

Application filed September 13, 1919. Serial No. 323,540.

To all whom it may concern:

Be it known that I, CHARLES J. EISENHAUER, a citizen of the United States, residing at Lebanon, in the county of Lebanon and State of Pennsylvania, have invented 5 certain new and useful Improvements in Knife-Sharpener, of which the following is a specification.

My invention relates to improvements in 10 knife sharpeners and more particularly to devices of this type adapted for sharpening bread and meat knives.

The object of my invention is to provide 15 a simple device of this character by which knives can be sharpened quickly and easily, which is automatically adjustable to accommodate knives of different bevels or thickness.

Another object of my invention is to provide 20 a knife sharpener, the movable parts of which are completely inclosed thus rendering the device practically "fool-proof."

Other and further objects and advantages 25 will be in part obvious and in part described as the specification is proceeded with.

In the accompanying drawings:

Figure 1 is a perspective view of the invention;

Fig. 2 is a front elevation with the front 30 plate of the casing removed;

Fig. 3 is a section taken on the line 3—3 of Fig. 2; and

Fig. 4 is a perspective view of one of the 35 slidable blocks removed from the casing.

Referring more particularly to the drawings in which like reference numerals represent similar parts throughout the several views, 5 denotes a base plate mounted upon which is a rectangular casing 6 comprising 40 end plates 7, side plates 8 and top plate 9, preferably of wood. The casing is divided centrally by a vertical slot or space 10 thus forming two communicating compartments 11 and 12.

Each compartment 11 and 12 is provided 45 with guideways 13 and 14 formed on the bottom face of the top plate 9 and the top face of the base plate 5 respectively, at opposite ends of the casing. The guideways 50 may be formed in any suitable manner as by means of spaced strips 30.

A pair of blocks 15 and 16 are slidably mounted within the guide ways by means of strips 17 and 18 attached to the top and

bottom edges of the blocks. The inner faces 55 19 and 20 of these blocks are inclined or beveled from top to bottom and to these beveled faces a pair of carborundum stones 21 and 22 are attached by means of screws or the like 23. The stones occupy or cover 60 about one half the width or face of the blocks, the other half being cut away at an oblique angle at their lower edges, as at 24 and 25, to permit of movement of the blocks and stones toward each other 65 beyond the center of the casing, under the action of coil springs 26 and 27. The location of the stones 21 and 22 is such that when the blocks have approached each other to the limit of their forward or inward 70 movement, the lower half of the face 20 of the block 16 seats within the cut away portion of the block 15 and the lower half of the face 19 of block 15 seats within the cut away portion of the block 16, thus causing 75 the stones to cross at an oblique angle.

In order to sharpen a knife, the blade thereof is inserted in the slot 10, and drawn backward and forward a few times between the reversely inclined crossed stones 21 and 22. 80 Downward pressure exerted on the knife by the operator causes the blocks to slightly reciprocate in their guide ways in an obvious manner, thus permitting the carborundum stones to accommodate themselves to 85 knife blades of different bevels.

Having thus described my invention, what I claim is:

1. A knife sharpener comprising a casing, 90 a pair of opposed sliding blocks in said casing, inclined sharpening stones on said blocks, said blocks having reversely located cut away portions to permit said stones to cross each other.

2. In a knife sharpener, a casing comprising side and end wells and top and bottom walls, said casing having a vertical slot passing through said top wall and said side walls, guide ways in said top and bottom wall, a pair of opposed blocks having means 100 on their ends slidably engaged in said guide ways, said blocks having reversely inclined opposed faces, sharpening stones attached to said faces, said blocks having reversely located cut away portions to permit said 105 stones to cross each other.

CHARLES J. EISENHAUER.
